UNITED STATES PATENT OFFICE.

GERTRUDE H. OWENS, OF ELKINS, WEST VIRGINIA.

SHIPPING-BAG.

1,317,641.

Specification of Letters Patent. Patented Sept. 30, 1919.

Application filed June 8, 1918, Serial No. 238,957. Renewed August 1, 1919. Serial No. 314,730.

To all whom it may concern:

Be it known that I, GERTRUDE H. OWENS, a citizen of the United States, residing at Elkins, in the county of Randolph and State 5 of West Virginia, have invented certain new and useful Improvements in Shipping-Bags, of which the following is a specification.

This invention relates to shipping bags, and more particularly to a container or bag 10 adapted to be used for shipping articles by parcel post.

One of the main objects of the invention is to provide a bag of the character stated which may be produced at small cost and 15 may be readily secured in closed position so as to effectually prevent loss of the contents thereof.

Further objects will appear from the detailed description.

20 In the drawings:—

Figure 1, is a side view of a bag constructed in accordance with my invention in open condition, with the closure flaps extended.

25 Fig. 2, is a similar view with the bag in closed condition.

Fig. 3, is a transverse vertical section on line 3—3 of Fig. 2.

Fig. 4, is a view similar to Fig. 1, taken 30 from the opposite side of the bag.

Fig. 5, is a view similar to Fig. 2 taken from the opposite side.

Fig. 6, is a fragmentary end view showing the upper corner of the bag as gathered.

35 Fig. 7, is a fragmentary detail section showing the inner pocket of the inner closure flap.

The bag is preferably made of some suitable heavy fabric, such as canvas. This bag 40 is provided with the end pieces 2 and has its sides 1 extended to provide closure flaps 3 and 4 which extend a considerable distance beyond the upper edge of the body portion of the bag. Strips 5 and 6 of fabric are 45 secured to the outer face of the side of the bag of which flap 3 is a continuation, these strips being so stitched as to provide alined keepers 7 for the reception of securing straps 8 which are secured at their ends 9 to 50 the outer face of the side of the bag, each of these straps being provided adjacent its fixed end with a buckle 10. Flap 3 is provided, at its outer edge, with a strip 11 similar strips 5 and 6 which is also stitched 55 so as to provide keepers 12 for the reception

of the securing straps. Strips 13 and 14 similar to the strips 5 and 6 are secured on the opposite sides of the bag and stitched to provide alined keepers 15 which receive the straps 8, a strip 16 similar to strip 11 being 60 secured at the outer edge of flap 4, and stitched to provide the keepers 17 for the reception of the securing straps. Flap 3 is further provided on its outer face with an address tag 18 secured thereto, a similar tag 65 19 being secured to the outer face of flap 4.

In using this device, after the goods have been placed in the body of the bag, flap 3 is turned inwardly and downwardly into the bag so as to extend across the upper end 70 thereof, thus providing a closure member for preventing escape of the contents of the bag, as in Fig. 3. Flap 4 is then turned downwardly at the upper end of the bag in the opposite direction so as to extend over 75 flap 3, the two flaps thus providing a double closure for the bag. The address to which the bag is to be sent, is then written or printed upon the tag 19, after which the straps 8 are passed through the keepers 17 80 and 7 of the strips 16 and 6, respectively, the free ends of these straps being then secured through the buckles 10. In this manner, the bag may be readily secured closed so as to effectually prevent all danger of the 85 loss of contents thereof, and may be quickly and easily opened when it reaches its destination.

When it is desired to return the bag, the operation above described is reversed, so that 90 flap 4 will be positioned inside of the bag, flap 3 being outside so as to expose the tag 18 upon which the original sender's name has been inscribed and to whom it is desired to have the bag returned. The bag may thus 95 be readily sent back and forth between two given addresses by the simple expedient of reversing the flaps so as to expose the name and address of the original sender, or of the original recipient, as desired. To insure 100 tight closure of the flaps, flap 4 is provided on the inner face of its outer edge with a plurality of snap sockets 21, which are adapted to engage coöperating studs 22 secured to the outer face of the opposite side 105 of the bag, flap 3 being provided with similar sockets 23 adapted to engage over coöperating studs 24 secured on the other side of the bag. As will be noted more clearly from Figs. 3 and 7, flap 3 is provided with 110

a lining in the shape of a supplemental piece of material 3^a secured to the inner face thereof, this material being stitched to the flap at its ends, and its edge adjacent the outer edge of the flap. This serves to provide a pocket 3^b which, when the flap is folded downwardly and inwardly into the upper end of the bag, is adapted to receive smaller articles which may be readily placed therein. The flap 4 is provided with a similar piece of material 4^a secured to the inner face thereof which serves to provide an upwardly opening pocket when the latter flap is folded downwardly and inwardly into the upper end of the bag. In Fig. 6 of the drawings, I have shown the upper portion of the end piece 2 of the bag as being gathered as at 2^a. This serves to slightly reduce the upper end of the bag so as to provide a somewhat tighter closure between the flaps and the upper edge of the bag. This gathering may be employed or not as desired, as will be evident, though I prefer to use it

where comparatively small articles are to be shipped.

25

Having thus described my invention what I claim as new and desire to secure by Letters Patent is:—

A bag comprising a bottom, ends gathered at their upper portions, sides connecting the edges of the ends and each having a closure flap integrally continuing its upper portion and of a length to pass across the mouth of the bag and over or under the other flap at will; and a supplemental piece of fabric secured at its lower edge inside each flap and constituting a pocket for use on the innermost flap combined with means for fastening the parts in closed condition.

30

35

In testimony whereof I affix my signature in presence of two witnesses.
